CLAIM

The ornamental design for a round backdrop cover, as shown and described.

DESCRIPTION

FIG. 1 is a front perspective view of a round backdrop cover, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is an enlarged view of detail 8 in FIG. 3; and,

FIG. 9 is a rear perspective view thereof.

The broken lines shown in the drawings depict environment and form no part of the claimed design. The broken lines in the form of a broken line circle seen in FIG. 3 and FIG. 8 are for the purpose of disclosing enlarged detailed views and form no part of the claimed design.

1 Claim, 7 Drawing Sheets
